US00D991314S

(12) **United States Design Patent** (10) Patent No.: **US D991,314 S**
(45) Date of Patent: ** Jul. 4, 2023

(54) **CAMERA**

(71) Applicant: **Shenzhen Oceanwing Smart Innovations Technology Co., Ltd**, Shenzhen (CN)

(72) Inventors: **Qisheng Peng**, Shenzhen (CN); **Chenyu Zhang**, Shenzhen (CN); **Sang Min Yu**, Shenzhen (CN)

(73) Assignee: **Shenzhen Oceanwing Smart Innovations Technology Co., Ltd**, Shenzhen (CN)

(**) Term: **15 Years**

(21) Appl. No.: **29/816,412**

(22) Filed: **Nov. 22, 2021**

(30) **Foreign Application Priority Data**

Jun. 17, 2021 (CN) 202130375660.9

(74) Attorney, Agent, or Firm — Banner & Witcoff, Ltd.

(57) **CLAIM**

The ornamental design for a camera, as shown and described.

DESCRIPTION

FIG. 1 is a front top perspective view of a camera showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along line 9-9 of FIG. 3.

The broken lines depicting the remainder of the camera form no part of the claimed design.

1 Claim, 9 Drawing Sheets
